Fig. 2.

Fig. 3.

Des. 185,266

PAGE 3

FIG. 6.

Fig. 1 is a front elevational view of a can opener or similar article embodying the new design.

Fig. 2 is a side elevational view thereof viewed from the left in Fig. 1.

Fig. 3 is a side elevational view thereof viewed from the right in Fig. 1.

Fig. 4 is a top plan view thereof.

Fig. 5 is a bottom plan view thereof.

Fig. 6 is a perspective view thereof showing the can opener supported on optional mounting legs which are illustrated in dotted lines.

The dominant features of the design residue in the portions shown in full lines.

We claim:

The ornamental design for a can opener or similar article, substantially as shown and described.
